(57) **CLAIM**

The ornamental design for a laminating clamp, as shown and described.

DESCRIPTION

FIG. 1 is a perspective view of a laminating clamp, with the front at the right side of the figure, showing my new design;

FIG. 2 is a side view thereof;

FIG. 3 is the opposite side view thereof;

FIG. 4 is a front view thereof, enlarged to better show details;

FIG. 5 is a rear view thereof;

FIG. 6 is a top view thereof, further enlarged to better show details; and,

FIG. 7 is a bottom view thereof.
